[57] CLAIM

The ornamental design for a traffic cone, as shown and described.

DESCRIPTION

FIG. 1 is a front perspective view of a traffic cone in its extended condition as employed for operation showing my new design;

FIG. 2 is a top plan view thereof;

FIG. 3 is a front elevational view thereof, it being understood that the rear and both side elevational views are identical thereto;

FIG. 4 is a bottom plan view thereof; and,

FIG. 5 is a front perspective view thereof shown in a collapsed condition.

FIG-1

FIG-2

FIG-3

FIG-5

FIG-4
